(57) **CLAIM**

The ornamental design for a device for sorting blood collection tubes, as shown and described.

DESCRIPTION

1. Medical apparatus and equipment.

1.1 is a front view of a Device for sorting blood collection tubes;

1.2 is a right side view thereof;

1.3 is a perspective view thereof;

1.4 is a left side view thereof;

1.5 is a top view thereof.
